MATERNITY PANTY GARMENT

Ilamae W. Jacobson, Minneapolis, Minn., assignor
to Kickernick, Inc., Minneapolis, Minn., a cor-
poration of Minnesota

Application April 15, 1948, Serial No. 21,168

3 Claims. (Cl. 2—224)

1

This invention relates to women's undergarments and particularly to a panty garment especially designed for pregnant women.

It has long been a problem for pregnant women to retain the upper portion of their panty garments up around their waist especially in the later stages of the pregnancy. The bulging of the expectant mother tends to pull the conventional garments down and this is both uncomfortable and unsightly.

It is an object of my invention to provide a novel and improved panty garment especially designed for use by pregnant women throughout the entire period of the pregnancy and which is particularly adapted to permit the upper extremity thereof to be maintained in comfortable position above the waist of the wearer even in the last stages of the pregnancy.

It is another object to provide a maternity panty garment for women having the front panel thereof substantially enlarged both laterally and longitudinally to provide fullness for future expansion and having a plurality of arcuately shirred segments vertically spaced across the lower portion of said enlarged front panel, to resiliently gather the surplus material of the garment and permit the same to fit snugly even though said garment is not fully filled out while providing ample fullness for the later stages of the pregnancy.

It is still a further object to provide a panty garment for pregnant women made from a plurality of interconnected sections, the front sections being substantially longer than the back sections to provide the necessary vertical fullness for future expansion.

These and other objects and advantages of my invention will more fully appear from the following description made in connection with the accompanying drawings wherein like reference characters refer to the same or similar parts throughout the several views and in which;

Fig. 1 is a front elevational view of my improved maternity panty garment shown as worn by a woman in the early stages of pregnancy;

Fig. 2 is a side elevational view of the garment and woman shown in Fig. 1;

Fig. 3 is an elevational view as viewed partially from the front and partially from the

2

side; showing my panty garment as it appears when worn by a pregnant woman in the later stages of her pregnancy;

Fig. 4 is a bottom plan view of the garment illustrated in Fig. 1 to Fig. 3 inclusive;

Fig. 5 is a fragmentary transverse vertical sectional view taken through one of the elastic shirring elements showing the attachment thereof to the front panel of the garment;

Fig. 6 is a plan view of the back section of the pattern laid out flat;

Fig. 7 and Fig. 8 are plan views of the side sections of the pattern laid out flat;

Fig. 9 and Fig. 10 are plan views of the front panel sections of the pattern laid out flat; and,

Fig. 11 is a plan view of the crotch section of the pattern laid out flat.

As illustrated in the accompanying drawings, I provide a maternity panty garment made from a plurality of sections of soft, pliable material secured together as by being sewed. In the form of the invention illustrated, a back panel 14 as shown in Fig. 6 is provided having a top edge 15, side edges 16 and 17 respectively, and bottom edges 18 and 19 with the crotch receiving center portion 20. As shown in Figs. 7 and 8, I provide two side-sections 21 and 22 respectively, and having the top edges 23 and 24 respectively, the side edges 25 and 26 respectively, front edges 27 and 28 respectively and the bottom edges 29 and 30 respectively with the crotch attachment portions 31 and 32 respectively. Two front sections 33 and 34 respectively, are provided in the form illustrated and are best shown in Figs. 9 and 10. The sections 33 and 34 have top edges 35 and 36 respectively, outer side edges 37 and 38 respectively, center edges, 39 and 40 respectively, and bottom edges 41 and 42 respectively. I provide a crotch insert section 43 having the back edge 44 and the front edge 45 with the two side edges 46 and 47.

From the pattern sections illustrated in Fig. 6 to Fig. 11 inclusive, it will be apparent that the front portion of the garment will be substantially longer than the rear portion. In assembling the garment, the two side edge portions 25 and 26 of side sections 21 and 22 are respectively joined to the side edge portions 16 and 17 of the back panel 14 as by being sewed thereto. The front sections 33 and 34 are joined as

by having their front edges 39 and 40 sewed together to form a front panel for the garment. This front panel is interposed between the two side sections 21 and 22 and is interconnected therewith as by having the side edge sections 37 and 38 of front sections 33 and 34 respectively sewed to side edges 27 and 28 of said side sections 21 and 22. The crotch section 43 is then connected to the garment as by having back edge 44 sewed to the central bottom edge portion 20 of back panel 14 and by having the crotch attachment portions 31 and 32 of the side sections 21 and 22 sewed to the respective side portions of the front edge 45 of crotch section 43. The central portion of front edge 45 is sewed to the two bottom edges 41 and 42 of the front panel 33 and 34 which form a continuous bottom edge of the front panel. It will be seen that the bottom edge of the front panel will be gathered considerably as best shown in Fig. 4. The bottom edges 18 of back panel 14, and 29 of side panel 21 combine with the side edge 46 of the crotch section 43 to form one leg opening and the bottom edges 19 and 30 respectively of the back panel 14 and side section 22 combine with side edge 47 of crotch section 43 to form the other leg opening. In the style of the garment illustrated, the leg openings and the trunk opening formed by the inter-connected respective sections have a highly resilient elastic material sewed around the marginal portion thereof to resiliently gather the material surrounding the respective openings and lightly embrace the portion of the wearer surrounded thereby at the respective openings. The elastic gathers around the respective openings are adjusted to apply only very slight pressure against the legs and trunk of the wearer.

Before the front panel is joined to the rest of the garment, the lower portion thereof is drawn together by a plurality of spaced highly resilient easily stretchable elastic elements to form shirring in the lower portion of the front panel. These elastic shirring elements are sewed to the front panel in the form of concentric arcuately curved segments curving upwardly toward the center thereof as best shown in Figs. 9 and 10. The natural tendency of the arcuate elastic shirring elements is to exert straight line pull to form the shirring in the lower portion of the front panel. The upper portion of the elongated front panel will thus be pulled down by this tendency of the elastic elements to straighten out, and said front panel will be gathered vertically as well as laterally, so that when the fullness of the front panel is not filled out, the panty garment will fit snugly and smoothly while at the same time providing ample room for expansion necessary for the later stages of the pregnancy.

It will be seen that I have provided a highly efficient maternity panty garment which can be worn by an expectant mother throughout the entire period of the pregnancy without any uncomfortable downward pulling of the upper extremity thereof or any uncomfortable bunching of the garment. None of the conventional panty garments has the necessary fullness in the front panel thereof to permit the top portion of the garment to be retained up around the waist of the wearer during the later stages of the pregnancy. These conventional garments are pulled down by the outwardly protruded bulge formed by the fetus within the expectant mother be-

cause they do not have additional length or fullness in the front panel. My improved garment with the elongated front panel can be pulled up above the bulge and has the necessary fullness to eliminate any downward pulling on the front panel and the discomfort of having the elastic top tightly stretched across substantially the largest portion of the wearer. Also, when the elastic top of conventional garments extends across the largest portion of the wearer, a line will be formed which will be clearly visible through the outer clothing of the wearer because the said outer clothing will obviously be tight against the wearer at this largest point. The elastic shirring at the lower portion of the front panel does not in any way support the wearer but is merely provided to gather the excess material and to resiliently hold said material lightly against the lower trunk portion of the wearer. This provides a neat, snug fitting garment which has ample room for expansion for the later stages of the pregnancy and permits the wearer to wear the same garment throughout the entire period of the pregnancy and thus obviates the necessity of periodically buying larger garments which as we have shown would not solve the problem. My garment provides added fullness only in the front thereof and has only the conventional seat design. It would, of course, not have the excessive fullness across the seat that would be encountered by buying progressively larger sizes.

It will, of course, be understood, that various changes may be made in the form, details, arrangement and proportions of the parts without departing from the scope of my invention.

What I claim is:

1. A maternity panty garment comprising a seat and back portion, side portions and a front panel for covering the central portion of the abdomen of the wearer, said front panel being formed from two longitudinal sections of material of substantially greater length than the back portion of the garment to provide longitudinal fullness and having joined longitudinal edges at the front of the garment, at least the side edges of said sections opposite said joined front edges being generally convexly curved throughout their lengths to form diminished top and bottom end portions and provide, when joined, additional lateral fullness in the abdominal portion of the garment, and a plurality of spaced, highly elastic elements connected with said front panel in the form of substantially upward curved concentric arcs to resiliently shirr the excess material in the front panel of the garment, both downwardly and laterally to lightly embrace the body of the wearer at all times.

2. A maternity panty garment comprising a seat and back portion, side portions and an elongated, central, front abdominal panel extending upwardly from the crotch of the garment and connected with said side portions, said panel having a widened intermediate portion to provide a lateral fullness in said panel and being of a length to provide also longitudinal fullness in said panel and a plurality of spaced elastic elements extending transversely across the lower portion of said panel and attached thereto to shirr the excess material in accordance to the specific needs of the wearer and to cause the abdominal portion of said garment to lightly embrace the wearer at all times.

3. A maternity panty garment comprising a back portion, side portions, and a central front panel substantially longer than said back portion

and having the side edges thereof connected with said side portions and having additional lateral fullness in the central portion thereof, said garment having a pair of leg openings and a trunk opening, a plurality of spaced highly elastic elements connected with said front panel in the form of substantially upwardly curved concentric arcs to resiliently draw the excess material provided in the front portion of the garment together both downwardly and laterally to lightly embrace the body of the wearer at all times.

10 ILAMAE W. JACOBSON.
